1.985.919

ARCH SUPPORTING SOLE UNIT

Frank G. Delbon, Brooklyn, N. Y.

Application December 1, 1933, Serial No. 700,491

2 Claims. (Cl. 36—71)

This invention relates to shoes, and particularly to improvements therein for enabling the foot to better bear the weight of the body than heretofore. More particularly, the invention relates to an article of manufacture for being built into shoes so as to support the foot in an improved manner.

Most articles of this nature go no farther than to "shore up" or buttress the muscles in and near the ball or the heel of the foot after they have taken all the weight of the body, or after the muscles have fallen, the major part of the weight being thrown directly onto the ball of the foot. Also in all shoes known to me, that portion of the shoe that lies in the instep region or the middle third of the foot, in which is applied at least three-quarters of the weight of the body, and which is the broadest part of the natural shape of the human foot, is intentionally constructed as the very narrowest part of the shoe, with the result that the abductor and other muscles in the plantar arch and in the metatarsal arch, are so cramped and unsupported that "foot trouble" has become the rule instead of the exception.

25 I have discovered that inasmuch as the greatest part of the weight of the body comes on the tarsal region and not on the metatarsal region or the heel region, that instead of being the least supported and most cramped part of the shoe, the
30 region in the middle third of the foot is best made the widest part of the shoe; that is, the total area, though not necessarily the greatest horizontal width (as will hereinafter become apparent), of this portion of the shoe should be greater than
35 that in the sole or other part of the shoe, and that the muscles in this region, instead of being cramped by narrow insteps and left unsupported by locating all support directly underneath only the main muscles, should be allowed longitudinal and transverse space and should have a strong, yet
40 resilient support in all directions, and not merely directly beneath them.

45 It is the chief object of this invention to provide an article for being built into shoes which will provide greatest, yet differentiated, strength and greatest room in those parts of the foot where the greatest weight and strain come, instead of throwing this strain onto parts of the foot not anatomically built to stand these strains.

50 A particular object of the invention is to provide an article which will prevent falling of the plantar arch, of the metatarsal arch, and of the abductor muscle, and notwithstanding such complete support, will have differential weight resisting power in certain places to prevent cramping one muscle due to supporting another.

A further particular object of the invention is to provide an insole-like article adapted to be made and sold separately to shoe-manufacturers for them to build it into shoes, which will be inexp-
60

sive and rugged, yet without rendering its assembly with the rest of the shoe parts difficult and expensive.

Several of the presently-preferred embodiments are shown, merely by way of illustration, in the accompanying drawings, but the invention is limited in its embodiments only by the scope of the subjoined claims. In these drawings,

Fig. 1 is a perspective of one embodiment of the article;

Fig. 2 is a section on line 2—2 thereof;
Fig. 3 is a bottom plan view thereof;
Fig. 4 is a section on line 4—4 of Fig. 2;

Fig. 5 is a perspective showing the assemblage of said article;

Fig. 6 is a perspective of a modification; Fig. 7 is a section on line 7—7 of Fig. 6; Fig. 8 is an enlarged perspective of one of the parts shown in the preceding views.

Fig. 9 is a bottom plan view of another modification;

Fig. 10 is a section on line 10—10 of Fig. 9;
Fig. 11 is a section on line 11—11 of Fig. 10;
Fig. 12 is a bottom plan view of another modi-
fication.

Fig. 13 is a section on line 13—13 of Fig. 12; and Fig. 14 is a plan view of one of the elements of

The first embodiment shown above comprises a single integral piece of leather 1, specially

a single integral piece of leather 1, specially shaped as shown, that is, with the forward portion 2 shaped like the forward portion of an insole, the middle portion protruding on one side 3 under the abductor muscle on the inner side of

3 under the abductor muscle on the inner side of the foot, and the opposite side, instead of being straight, also being slightly protuberant as shown at 4 for fitting under the fifth metatarsal bone.

at 4 for fitting under the fifth metatarsal bone. The rear end of the leather is made more the shape of the os calcis and more dished than is usual, and is made broader and more oval than

usual, and is made broader and more oval than usual. The leather is split along the horizontal plane 5 for more than half its length into two equal halves as shown in Fig. 5, and pressed and

equal halves, as shown in FIG. 5, and pressed and molded to form a matrix for a more or less rigid member 6 made preferably of duralumin, but advantageously of springy steel or, if desired, of aluminum or aluminum alloy.

The member 6 has a peripheral configuration conforming and following generally the outline of the bottom of the leather, as shown in Fig. 5.

of the bottom of the leather, as shown in Fig. 3, and has a peripherally curved portion 7 that is also curved in the longitudinal and transverse planes, as shown more clearly in Fig. 8, which

planes, as shown more clearly in Fig. 8, which fits under and supports the abductor muscle of the foot, preventing pronation. The opposite side is also slightly protuberant, as shown at 8 and

is also slightly protuberant, as shown at 8, and prevents supination. The forward end of the metal member 6 has a slightly upwardly turned portion 9 for forming a table slightly back of the metatarsal arch onto which a metatarsal pad as

described in my Patent No. 1,771,673, may be fitted as described therein. The forward end is also provided with a rivet hole 10 which divides the table into two tongues 11 and 12. The tongues 5 11 and 12, coacting with the formations 6 and 7 prevent pronation and supination, and yet provide a yielding flexible-resilient support under the metatarsal arch, instead of hurting or cramping the foot there. An aperture 13 may be left in the 10 heel for riveting thereto. Several apertures 30 are punched out near the ends of the rigid member 6 in such a manner that they form a small circular shaped opening on the top side of said member and form rough depressions or projections on 15 the underside. The depressions or projections on the underside of the member 6 form an opening having a rectangular outline so that when these projections grip the adjacent leather sheets all rotation of the several elements between them- 20 selves is prevented. Such a construction also tends to limit the possibility of the metal sheet from pulling away from the several leather sheets.

In Figs. 6 and 7, instead of slipping the metal member between halves of the leather, the article 25 consists of a single piece of leather 14, extending the full length of the foot, and a thinner piece of leather 15 attached by sewing 16 where shown, and the metal member 6 is slipped in between the 30 two and the article is adapted to be sewn to the shoe-upper, and the metal member thereby fixed in place, by a line of stitching 17.

In the embodiment shown in Fig. 9, instead of either placing the metal member between halves of the leather or on the top of the leather, as in preceding figures, it is placed on the bottom of the leather insole 18, and the member 19, made of leather and shaped as shown, is placed below it, and the member 19 and the member 18 are adapted to be sewn together and to the upper 40 along the line of stitching 8'. By these means the respective ends of the metal member are anchored and abutted at 20 and 21 (see rivets, Fig. 10) to the rigid part of the shoe and held between the two leather pieces. To provide support for the 45 metatarsal arch, the forward end of the bottom leather strip is thickened and rounded and shaped as shown in Fig. 9, to form a leather metatarsal pad 20'.

In Fig. 12, the same essential construction is 50 employed, but the leather is cut on the line 24, and a rubber metatarsal pad 25 similar to the one shown and described in my U. S. Patent No. 1,771,673, is attached over the end of the metal member, as, and for the purposes described in 55 that patent. In this embodiment, the metal member takes the form shown as 26, (Fig. 4) in which the side on the line of the fifth metatarsal bone on the outside of the foot is cut away to provide a resilient support as described in my 60 said patent, and there is a yoke 27 for fitting around the rivet or stud in the heel. Lightening and resiliency-giving formations 28 are provided in the support for the abductor muscle, as is shown most plainly in Fig. 14.

65 In all embodiments it is clear that there is provided, a leather member to act somewhat as the usual leather insole, and to which the upper is attached; and a metal arch member or bridge

member having a rigid abutment and anchorage directly under the os calcis and another such rigid abutment and anchorage just to the rear of the metatarsal arch. The weight of the foot is then received by the shoe first at the top of the arch and is distributed evenly between the ball and the heel, instead of all coming on the ball, as is usual, while simultaneously being spread laterally in the instep, instead of being cramped and bound as in the ordinary instep. The upwardly 10 arched formation on the inner side of the article prevents pronation and supports the abductor muscle, and the bulge on the outer side prevents the opposite faulting of the foot. The rear portion of the article is dished or cupped in to receive 15 and support the os calcis region and the article may be provided with either a leather or rubber metatarsal pad.

I claim:

1. In an arch-supporting sole unit, comprising 20 a laminated structure of several layers including a flexible and soft member for fitting under the sole of the foot, a sheet member of metallic material for reinforcing said first-mentioned member, said reinforcing member being located under 25 the middle third only of the foot, another flexible and soft member similar in size and shape to the said first mentioned member, all of said members being somewhat narrower at their ends and substantially wider at their middle sections, said 30 middle sections being extended outwardly and substantially wider than the corresponding sections for the shoe, said middle sections being also curved upwardly to thereby prevent pronation and supination of the foot of the wearer, headed 35 frictional piercing instrumentalities having a rectangular cross section, countersunk depressions in the metallic member having apertures of rectangular outline therethrough for permitting the 40 piercing instrumentalities to pass, and an open end slot in the forward end of the metallic member for registering with an anchoring means which combines the several layers into a composite 45 unit.

2. In an arch-supporting sole unit, comprising 45 a laminated structure of several layers including a split insole of flexible and soft material for fitting under the sole of the foot, a member of metallic material for reinforcing the split insole, said reinforcing member being located under the 50 middle third only of the foot, all of said members being somewhat narrow at their ends and substantially wider at their middle sections, said 55 middle sections being extended outwardly and substantially wider than the corresponding section for the shoe, said middle sections being also curved upwardly to thereby prevent pronation and supination of the foot of the wearer, headed frictional piercing instrumentalities having a rectangular cross section, countersunk depressions in the metallic member having apertures of rectangular outline therethrough for permitting the 60 piercing instrumentalities to pass, and an open slot in the forward end of the metallic member for registering with an anchoring means which 65 combines the several layers into a composite unit.

FRANK G. DELBON.
